KARL BÖHLE, OF ESSEN-ON-THE-RUHR, GERMANY, ASSIGNOR TO FRIED. KRUPP AKTIENGESELLSCHAFT, OF ESSEN-ON-THE-RUHR, GERMANY.

PRESS FOR STAMPING FLANGED END PLATES AND THE LIKE.

Application filed December 6, 1920. Serial No. 428,647.

To all whom it may concern:

Be it known that I, KARL BÖHLE, residing at Essen-on-the-Ruhr, Germany, a citizen of the German Republic, have invented 5 a certain new and useful Improvement in a Press for Stamping Flanged End Plates and the like, of which the following is a specification.

The invention relates to flanging presses 10 for the manufacture of sheet metal plates flanged on the outer rim, which presses comprise a female die member having an annular flanging portion and a stamp having a flanging portion adapted to enter said 15 flanging portion of the female die member in axial direction, said flanging portions being separated from each other by a clearance when the flanging portion of the stamp has entered the annular flanging portion of 20 the female die member, one of said flanging portions being rigid and the other being resilient round its whole circumference whereby the width of said clearance may be automatically enlarged during the press- 25 ing operation. The invention consists in providing means operable at will for changing the shape of said resilient flanging portion in the sense of diminishing said clearance whereby the advantage is attained that 30 the resilient flanging portion may be formed with comparatively small resiliency and correspondingly small cross sectional dimensions.

One embodiment of the subject matter 35 of this invention is shown by way of example in the accompanying drawing, in which—

Fig. 1 is a diagrammatic axial longitudinal section of the essential parts of the press 40 here entering into consideration,

Figs. 2 and 3 similar views illustrating different working positions of said parts.

The portion of the stamp adapted to be applied to the flanged edge a^1 of the work 45 A is formed by a steel ring B of comparatively small cross sectional dimensions, which is slotted obliquely in suchwise that the surfaces of separation b^1 and b^2 of said ring will spring apart for a certain measure 50 when subject to no pressure. The shell surface b^3 of the ring B remote from the longitudinal axis of the press has conical shape. Every shell line of this conical surface is inclined relatively to the longitudinal 55 axis of the press at an angle, which cor-

responds to the angle defined by the shell lines disposed in the same axial plane and appertaining to the outer and inner shell surface of the flanged edge a^1 of the work A after the pressing operation owing to the increase which has taken place in the thickness of the plate toward the unsupported end of the flanged edge. In a like manner, the shell surface b^4 , which faces the longitudinal axis of the press, has also a conical shape, the longitudinal axis of which cone converging with the longitudinal axis of the shell surface b^3 of ring B and also with that of the press. The support C of ring B, forming a part of the stamp is provided 65 with a conical surface c^1 , disposed coaxially to the conical surface b^4 of the ring B, and the shell lines of which define conjointly with the longitudinal axis of the press the same angle of inclination as the shell lines 70 of the conical surface b^4 . When the ring B is subject to no pressure, there is formed an annular clearance of conical configuration and of definite breadth intermediate the two conical surfaces b^4 and c^1 . The support C is provided with a lateral edge c^2 75 protruding beyond the conical surface c^1 : the front end c^2 of this edge facing the ring B is, in the position of the parts shown in Figs. 1 and 2, for a certain distance remote 80 from the front end b^5 of the ring B which faces the edge c^2 . In the clear space between the edge c^2 and the ring B there are interposed pieces or blocks D. Further a plate F is connected to the support C by means 85 of screw bolts E, which plate is adapted to engage a bored out section b^6 of the ring B. The screw bolts E are tightened only sufficient to prevent an axial displacement of the ring B relatively to the support C, 90 while admitting said ring to execute radial movements. That particular portion of the matrix destined to be applied to the flanged edge a^1 of the work, consists of a rigid cylindrical ring G. The dimensions of the 95 two pressing members B and G are so chosen, that the maximum radius of the conical surface b^3 of the ring B, the stamp being subject to no load, will be smaller by the depth of the plate thickness of the work 100 A than the radius of the ring G.

When the stamp is lowered, the work A heated to a red heat and lying on the matrix is forced by the ring B of the die into the ring G of the matrix (Fig. 1). During this 110

operation every diameter of a circle described on the edge prior to the flanging operation, concentrically to the longitudinal axis of the press, suffers a diminution of its extent. Now this diminution, causes an increase in the plate thickness of the work from the bottom toward the unsupported end thereof and results further in the flanged edge of the work tending to bend itself in 5 the manner of a corrugation, so that its free front face will no longer appear confined by two concentric circles, but by two undulations. Owing to its comparatively trifling cross sectional dimensions, the elasticity of 10 the ring B will prove inadequate to prevent such a configuration. Consequently, when the stamp descends, ring B is pressed together by the parts of the corrugations approaching the longitudinal axis of the press. 15 In the course of this action, the conical surface b^4 of the ring B approaches the conical surface c^1 of the support C, until toward the end of the lowering motion of the stamp both surfaces make contact (Fig. 2). Here- 20 upon, the press is brought to a stop, the intermediate blocks D are removed and at the same time the holder (not shown) on which the work rests, is secured in its position, so that the work A and the ring B resting on 25 the work, are prevented from executing any axial displacement in the direction of the working stroke of the press. Upon this, the press is again set into motion. The conical surface c^1 of the support C, which now alone 30 continues its path conjointly with the stamp now cooperates with the conical surface b^4 of the ring B after the manner of a wedge, and expands the ring in the radial direction. 35 As a result, the wave shaped configurations 40 in the flanged edge are removed and the flanged edge of the work is forced with its entire outer shell surface against the cylindrical inner wall of the ring G of the matrix, so that it obtains a cylindrical external 45 shell surface (Fig. 3). When, at the end of the lowering motion of the stamp, the plate F has attained the bottom of the work, the edge c^2 of the support C at the same time bearing down on the ring B, the press is 50 brought to a stop, and the stamp moved back into its initial position. During this 55 operation, the conical surface c^1 of the support C primarily is brought out of engagement with the conical surface b^4 of ring B, whereupon as the return motion of the 60 stamp proceeds, the plate F bears up against the base portion of the bored out portion b^6 of the ring B and takes this latter along. Hereupon, the conical surface b^3 of the ring 65 B glides along the internal shell surface of the flanged edge a^1 of the work A, clamped in the matrix or else secured therein by means of a guide member, (said internal shell surface having now also obtained a 70 conical configuration owing to the increased

thickness in plate of the work), the ring B being pressed together in a radial sense for such a length of time until it has entirely stepped out of the flanged edge. As soon as the stamp has completed its return motion, 75 the intermediate blocks D are again inserted between the edge c^2 of the support C and the ring B, and the press is again ready for work.

Claims:

1. A flanging press for the manufacture of sheet metal plates flanged on their outer rim comprising a female die member having an annular flanging portion, a stamp having a flanging portion adapted to enter said flanging portion of the female die member in axial direction, said flanging portions being separated from each other by a clearance when the flanging portion of the stamp has entered the annular flanging portion of the female die member, one of said flanging portions being rigid and the other being adapted to elastically yield transversely to said axial direction round its whole circumference in the sense of increasing the clearance 90 left between it and the other flanging portion, whereby the width of said clearance may be automatically enlarged during the pressing operation, and means operable at will for changing the shape of said yielding flanging portion in the sense of diminishing said clearance.

2. A flanging press for the manufacture of sheet metal plates flanged on their outer rim comprising a female die member having a rigid annular flanging portion, a stamp carrying a flanging ring adapted to enter said flanging portion of the female die member in axial direction, said flanging ring being movable relatively to the stamp in axial direction between a rearward end position and a forward one, and adapted to elastically yield transversely to said axial direction round its whole circumference in the sense of increasing the clearance left between it and the flanging portion of said female die member, means for securing said ring in a readily detachable manner relatively to the stamp with respect to axial movement in its forward end position, and a wedge shaped portion arranged on the stamp and surrounded by said ring whereby said ring may be extended when moving from its forward end position to its rearward one.

3. A flanging press for the manufacture 120 of sheet metal plates flanged on their outer rim comprising a female die member having a rigid annular flanging portion, a stamp carrying a flanging ring resilient round its whole circumference and adapted to enter said flanging portion of the female die member in axial direction, said flanging ring being movable relatively to the stamp in axial direction between a rearward end position and a forward one, a collar arranged 125

on the stamp to which said ring is adjacent when in its rearward end position, removable blocks interposed between said collar and the ring for securing the ring relatively to the stamp with respect to axial movement in its forward end position, and a wedge shaped portion arranged on the stamp and surrounded by said ring whereby said

ring may be extended when moving from its forward end position to its rearward one. 10

The foregoing specification signed at Es-
sen, Germany, this 23rd day of July, 1920.

KARL BÖHLE.
